FLOUR SIFTER ATTACHMENT FOR
ELECTRIC MOTORS

Orval C. Bond, Santa Barbara, Calif.

Application April 22, 1947; Serial No. 743,103.

3 Claims. (Cl. 209—358)

1

This invention relates to a sifting device, and more particularly to a sifting attachment adapted to be utilized in conjunction with electric mixers or the like.

A primary object of this invention is the provision of an improved power-driven sifter for flour, sugar, and similar dry pulverized materials.

An additional object of the invention is the provision of such a construction which may be utilized with a conventional electric food mixer and used simultaneously with the operation of the mixer.

A further object of the invention is the provision of such a device provided with a plurality of sifting elements, which may be readily removed and replaced, thus providing a relatively flexible implement, characterized by a plurality of sifting combinations.

An additional object of the invention is the provision of such a device which is sturdy and durable in construction, reliable and efficient in operation, relatively simple and inexpensive to manufacture, assemble and utilize, and which may be applied to and connected with a conventional electric mixer with a minimum of effort and difficulty.

Still other objects will in part be obvious, and in part be pointed out as the description of the invention proceeds, and shown in the accompanying drawings, wherein there is disclosed a preferred embodiment of this inventive concept.

In the drawings:

Figure 1 is a vertical sectional view taken substantially through the center line of one form of device embodying features of the instant invention, shown in association with a conventional electric mixer, parts of the latter being broken away.

Figure 2 is a sectional view taken substantially along the line 2—2 of Figure 1, as viewed in the direction indicated by the arrows.

Figure 3 is a sectional view taken substantially along the line 3—3 of Figure 1, as viewed in the direction indicated by the arrows.

Figure 4 is a fragmentary side view, partially broken away, showing a constructional detail.

Figure 5 is an enlarged fragmentary sectional view taken substantially along the line 5—5 of Figure 4, as viewed in the direction indicated by the arrows.

Similar reference characters refer to similar parts throughout the several views of the drawings.

Referring now to the drawings in detail, there is generally indicated at 10 an electric food mixer of

2

any desired conventional type, including a motor head 11, a supporting stand 12, an electric connecting cord 13, and a power take-off 14, of conventional design, provided with a slot 15 for connection with any desired implement, in normal use of the device, a fruit-juicing attachment.

The device of the instant invention includes a bracket 16, provided with a seating ring 17, adapted to engage in a recess in the top of the device adjacent the power take-off 14. The bracket has secured thereto, as by means of a set screw 18, an arcuate tube 19, within which is positioned a flexible drive shaft 20, the latter being provided with a tongue 21 for engagement with the slot 15 of the power take-off, in such manner that energization of the power take-off will drive the flexible shaft. The opposite end of the member 19 extends in an arc to a collar 25, carried by radially extending supporting strips 26 mounted in the upper portion of a tubular flour sifter 21. The parts may be held in related assembly as by means of a set screw 28, and the opposite end of the flexible drive shaft 20 engages a tongue 29 integrally associated with a rotatable shaft 30, extending downwardly along the center line of receptacle 21, and being provided at its lower extremity with a circular portion 31 journaled for rotation in a socket 32 carried by radially extending members 33, diametrically positioned across the bottom of the receptacle 21.

Interiorly of receptacle 21, adjacent the base thereof, is a ring 35, upon which is adapted to be positioned a sifting screen 36, engageable by a rotatable blade member 37, having a collar 38 provided with a squared aperture surrounding the shaft 30. If desired, a spacer ring 39 may be mounted on the screen 36 to carry an additional sifting screen 40, a collar 41, and blade 42, corresponding to blades 37 and collars 38. A further spacing ring 43 similar to the ring 39 may carry an additional ring 44, provided with a further rotatable blade 45 carried by a collar 46.

Obviously, the arrangement is such that any of the blades or their associated screens and spacer rings may be omitted if desired, and screens of varying meshes may be readily substituted for any or all of the previously described screens.

As best shown in Figure 5, means are provided for securing the blades against longitudinal displacement on the shaft 30, and take the form of a ball 50 seated in a recess in each of collars 38, 41, and 46, the ball being spring pressed, as by means of a spring 51 into engagement with a recess or detent 52 in the side of the shaft 30,

From the foregoing, it will now be seen that there is herein provided an improved power-driven flour sifter, readily adapted to wide flexibility of arrangement, which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. A flour sifter attachment for a motor food mixer having an opening in an upper part thereof and a motor driven shaft exposed in said opening, said attachment comprising a horizontally elongated bracket having a depending tubular bushing on one end adapted to be inserted in said mixer opening for supporting said bracket in laterally extending position on said mixer, a vertical sifter cylinder on the opposite or outer end of said bracket, a vertical sifter shaft supported for rotation in said cylinder and having agitator blades, a flexible shaft arched between the upper end of said sifter shaft and said driven shaft and extending downwardly through said tubular bushing, and means operatively connecting the related ends of said flexible shaft to said driven shaft and the upper end of said sifter shaft, respectively, said bracket comprising an upwardly arched handle for carrying said attachment when disconnected from said food mixer, said handle comprising an upwardly arched tube spacedly surrounding said flexible shaft and fixed at its opposite ends to portions on said bracket in protective relation to said flexible shaft.

2. A flour sifter attachment for a motor food mixer having an opening in an upper part thereof and a motor driven shaft exposed in said opening, said attachment comprising a horizontally elongated bracket having a depending tubular bushing on one end adapted to be inserted in said mixer opening for supporting said bracket in laterally extending position on said mixer, a vertical sifter cylinder on the opposite or outer end of said bracket, a vertical sifter shaft supported for rotation in said cylinder and having agitator blades, a flexible shaft arched between the upper end of said sifter shaft and said driven shaft and extending downwardly through said tubular bushing, and means operatively connecting the related ends of said flexible shaft to said driven shaft and the upper end of said sifter shaft, respectively, said bracket comprising an upwardly arched han-

5 dle for carrying said attachment when disconnected from said food mixer, said handle comprising an upwardly arched tube spacedly surrounding said flexible shaft and fixed at its opposite ends to portions on said bracket in protective relation to said flexible shaft, the end of said arched tube adjacent to said sifter shaft having a tubular bushing rotatably receiving the upper end of said sifter shaft and the adjacent end of said flexible shaft.

10 3. A flour sifter for attachment to a power take-off shaft of a motor driven food mixer comprising a horizontally disposed bracket, a vertically disposed sifter cylinder positioned adjacent one end of said bracket and dependingly supported therefrom, sifting means including a vertically disposed rotatable shaft positioned within said cylinder, an open-ended arcuate tubular handle having one end positioned in alignment with respect to said rotatable shaft and secured to said cylinder, the other end of said tubular handle being aligned with said power take-off shaft and supported in said bracket adjacent its other end, and flexible coupling means disposed within said tubular handle having one end operatively connected to said shaft and having the other end adapted to be coupled to said power take-off shaft.

ORVAL C. BOND.
